(57) CLAIM

The ornamental design for a drinking water bottle, as shown.

DESCRIPTION

FIG. 1 is a perspective view showing our new design, in a vertical orientation;

FIG. 2 is a side elevational view of the embodiment shown in FIG. 1;

FIG. 3 is a top view thereof;

FIG. 4 is a side elevational view of the embodiment shown in FIG. 2, with the bottle rotated approximately 90 degrees; and,

FIG. 5 is a side elevational view of the embodiment shown in FIG. 2, with the bottle rotated approximately 180 degrees.
